No. 1345

J. B. Sargent & Turnot Bradford, of New Britain Conn.
assor. to

J. B. Sargent, aforesaid
Letters Patent No. 1345, Dated Nov. 13th 1860.

The schedule referred to in these ~~Letters Patent~~ and making part of the same.

To all whom it may concern:

Be it known that J. B. Sargent and Turnot Bradford, of New Britain, County of Hartford, and State of Connecticut, have invented a new and original design for a Drawer Pull; and we do hereby declare that the following is a full, clear and exact description of the same, reference being had to the annexed drawing making a part of this specification:

The drawing is a perspective view of our improvement.

This drawer pull is made in one piece in the usual manner, our improvement relating only to the form or configuration thereof. A. is the usual rim or frame part, which is intended to be secured to the face of the drawer by screws which are to pass through holes (a) in the ends of the rim as shown in the drawing.

The rim or frame is made entirely open as shown except at its upper part, from which there rises a shell B of oval form, which covers about

one half of the open space of the rim. The shell B is made with and forms a part of the rim A, in the usual manner.

At the outer part of both extremities of the rim A, portions of the rim are scalloped as indicated at b. b. c. c, and the lower part of the rim is brought down in an ornamental scroll form d d so as to form at the centre of the rim a graceful point e of V shape as shown in the drawing, the edges of the rim being slightly rounded, all as shown.

The upper edge of the shell is also provided with an ornamental raised head f as shown.

Having thus described our invention, what we claim is:

The ornamental design and configuration of the drawer

full herein shown and described.

Ex'd
